UNITED STATES PATENT OFFICE.

OMAR B. BUCHANAN, OF WILKINSBURG, PENNSYLVANIA, ASSIGNOR TO WESTINGHOUSE ELECTRIC & MANUFACTURING COMPANY, A CORPORATION OF PENNSYLVANIA.

SIGNALING SYSTEM.

Application filed August 18, 1921. Serial No. 493,234.

To all whom it may concern:

Be it known that I, OMAR B. BUCHANAN, a citizen of the United States, and a resident of Wilkinsburg, in the county of Allegheny and State of Pennsylvania, have invented a new and useful Improvement in Signaling Systems, of which the following is a specification.

My invention relates to wireless systems and more especially to wireless signaling systems.

In its broad aspect, the object of my invention is to provide simple and efficient means for controlling the radiation of energy from wireless transmission systems.

More specifically, one object of my invention is to provide an improved radio transmission system wherein the wave length of the radiant energy is maintained constant and wherein a uniform load is maintained upon the source of energy during the signaling and non-signaling periods.

Another object of my invention is to provide a signaling system which is especially adapted to arc transmission systems in that signaling may be effected without interrupting the operation of the arc.

Still another object of my invention is to provide a signaling system in which the sparking at the key contacts is reduced to a minimum.

According to my invention, I provide a simple and efficient signaling system which obviates many of the difficulties heretofore encountered. One way to practice my invention is to provide a source of radio-frequency currents and to associate in parallel relation therewith, an antenna or work circuit and an absorbing circuit, each of said circuits including an anti-resonant reactance device. Signals may be formed by selectively rendering said anti-resonant devices effective or non effective as impedance elements.

Other objects of my invention, as well as details of construction, whereby my invention may be practiced, will be apparent from the following description, taken in connection with the accompanying drawing and claims, wherein:

The single figure is a diagrammatic representation of circuits and apparatus embodying my invention, as applied to an arc-converter system.

In the drawing, I have shown a "work" 55 or radiating circuit 1 and an absorbing circuit 2, both in parallel and shunted around a source of radio-frequency currents 3. The source of radio-frequency currents 3 has, for purposes of illustration, been shown 60 as an arc converter comprising an arc 4 which may be energized from a source of direct-current energy 5 through a pair of choke coils 6.

The absorbing circuit 2 comprises a fixed 65 condenser 7, a tuning coil 8, an energy-absorbing element 9 and a parallel-resonant circuit 11, said last-mentioned circuit including a variable condenser 12 and a tuning coil 14. The resistance of the coil 14 70 is represented by a resistor 13 in series therewith. The resistance of the element 9 is such as to maintain a load upon the arc converter during the non-signaling period which is substantially equal to that upon 75 the arc during the signaling period.

The radiating circuit 1 comprises an antenna 15, a down lead 16, which connects the antenna 15 to an electrode 17 of the arc 4 and a ground conductor 18 which connects 80 the remaining arc electrode 19 to ground. The down lead 16 includes a parallel-resonant circuit 21, comprising an inductor 14a and a resistor 13a shunted by a condenser 12a, and a tuning coil 22.

A switching device 23 comprises stationary contact members 24 and 25 and a co-acting movable contact member or key 26. One terminal of the switch member 26 is connected to a point 27, which is common 90 to the radiating and absorbing circuits, while the other terminal may be actuated into engagement with the stationary contact members 24 and 25. The stationary contact members 24 and 25 are connected to 95 such points 28 and 29 in the radiating and absorbing circuits that the parallel-resonant circuits contained therein are selectively short circuited upon the operation of the key 26.

It will, of course, be understood that any approved form of switching device may be employed to effect the results accomplished by the particular switching device indicated in the drawing, and that my invention is not to be limited thereby.

In operation, the electrical time constants of the parallel-resonant circuits 11 and 21

- are adjusted to such value that the insertion of a parallel-resonant circuit 11 or 21, in series with either the energy-radiating circuit 1 or the energy-absorbing circuit 2, 5 causes the time constant of said energy-circuit to be greater than the time constant of the other energy-circuit which does not include a parallel-resonant circuit. It has been found that, when two oscillation 10 circuits are connected in parallel across an arc oscillator, only a very small part of the oscillating electromotive force of the arc is effective in the circuit having the larger time constant.
- 15 The resistances in the parallel-resonant circuits are beneficial in reducing the circulating currents produced by the small part of the arc electromotive force which is effective in the energy-circuit containing a 20 parallel-resonant circuit. Hence, when the key 26 is moved to short-circuit a parallel-resonant circuit, the circulating currents in the parallel-resonant circuit are of such magnitude that they may be short-circuited 25 without injury to the contact points.

When the short-circuiting path is opened, the condenser 12 or the condenser 12a prevents sparking at the contact points. However, if the oscillatory current builds up 30 too quickly in the corresponding parallel-resonant circuit, the oscillatory voltage across the switch may become large enough to break down the gap at the contact points after the switch becomes opened a very 35 slight amount. The resistors 13 and 13a are, therefore, made large enough to properly damp the oscillatory currents in the parallel-resonant circuits. Signals are transmitted by moving the switch back and forth in a 40 manner which will be obvious.

While I have shown only one embodiment of my invention, it is apparent that various changes and modifications may be made therein without departing from the spirit 45 and scope of my invention. I desire, therefore, that only such limitations shall be imposed thereon as are specifically set forth in the appended claims or are imposed by the prior art.

50 I claim as my invention:

1. The combination with a source of oscillatory currents, of a work circuit and an absorbing circuit, both in parallel and shunted around said source, each of said circuits including an impedance element having a predetermined electrical time constant, and means operable to render said impedance elements effective or ineffective, said means including a device for selecting the element to be effective and the element to be ineffective.

2. The combination with a source of oscillatory currents, of a work circuit and an absorbing circuit, both in parallel and shunted around said source, each of said circuits in-

cluding an impedance element comprising a parallel-resonant circuit, and means for selectively rendering said impedance elements effective or ineffective.

3. The combination with a source of oscillation currents, of a tuned work circuit and a similarly tuned absorbing circuit, both in parallel and shunted around said source, each of said circuits including similar impedance elements having similar electrical time constants, and means operable to render said impedance elements effective or ineffective, said means including a device for selecting the element to be effective and the element to be ineffective.

4. In a wireless transmission system, a source of oscillations, a radiating circuit connected to said source, an absorbing circuit shunted around said source, each of said circuits including impedance elements having predetermined electrical time constants, and means for, at will, short-circuiting either impedance element to render the circuit containing that impedance element oscillatory and to render the remaining circuit non-oscillatory.

5. The method of signaling by means of an arc device and antenna and absorbing circuits supplied by said device which consists in alternately inserting and removing parallel-resonant reactance devices in the respective circuits.

6. The combination with a source of oscillatory currents of a tuned work circuit, a tuned absorbing circuit, and means for causing the currents from said source to flow substantially in the one or the other circuit, said means including circuit connections for connecting said circuits in parallel across said source, an inductive impedance device shunted by a capacitive impedance device in series relation to the circuit connections for each of said circuits, and by-pass means for varying the effectiveness of said groups of parallel-connected impedance devices.

7. The combination with a source of oscillatory currents, of a tuned work circuit, a tuned absorbing circuit, and means for causing the currents from said source to flow substantially in the one or the other circuit, said means including circuit connections for connecting said circuits in parallel across said source, an inductive impedance device shunted by a capacitive impedance device in series relation to the circuit connections for each of said circuits, a by-pass path for each of said pairs of shunted impedance devices, and switching means for closing one path and opening the other and vice versa, the relations of reactances, being such that the time constant of either circuit, with the shunted impedance devices in series, is greater than the time constant of the other circuit with the shunted impedance devices short-circuited.

8. The combination with a source of oscillatory currents, of a tuned work circuit, a similarly tuned, equivalent-energy circuit, circuit connections for connecting said circuits in parallel across said source, parallel-resonant, reactive-impedance means tuned to approximately the same frequency as said circuits and connected in series relation to the circuit connections for each of said circuits, and controllable by-pass means for the respective parallel-resonant means.

9. The combination with a source of oscillatory currents, of a tuned work circuit, a similarly tuned, equivalent energy circuit, circuit connections for connecting said circuits in parallel across said source, parallel-resonant, reactive-impedance means tuned to approximately the same frequency as said circuits and connected in series relation to the circuit connections for each of said circuits, a by-pass path for each of said parallel-resonant means, and switching means for closing one of said paths and opening the other and vice-versa, each of said parallel-resonant means having a relatively small resistance and relatively large inductive and capacitive reactances, each of said circuits likewise having, in effect, a relatively small resistance and relatively large inductive and capacitive reactances, said quantities being so chosen that there is little tendency for the oscillatory currents to flow in the circuit having the open-circuited by-pass path.

10. The combination with an arc-oscillation generator, of a tuned work circuit, a tuned absorbing circuit and means for causing the currents from said generator to flow substantially in the one or the other circuit, said means including circuit connections for connecting said circuits in parallel across said generator, an inductive impedance device shunted by a capacitive impedance device in series relation to the circuit connections for each of said circuits, and by-pass means for varying the effectiveness of said groups of parallel-connected impedance devices.

11. The combination with an arc oscillation generator, of a tuned work circuit, a tuned absorbing circuit and means for causing the currents from said generator to flow substantially in the one or the other circuit,

said means including circuit connections for connecting said circuits in parallel across said generator, an inductive impedance device shunted by a capacitive impedance device in series relation to the circuit connections for each of said circuits, a by-pass path for each of said pairs of shunted impedance devices, and switching means for closing the one path and opening the other and vice versa, the relations of resistances and reactances being such that the time constant of either circuit with the shunted impedance devices in series is greater than the time constant of the other circuit with the shunted impedance devices short-circuited.

12. The combination with an arc oscillator, of a tuned work circuit, a similarly tuned equivalent-energy circuit, circuit connections for connecting said circuits in parallel across said oscillator, parallel-resonant, reactive-impedance means tuned to approximately the same frequency as said circuits and connected in series relation to the circuit connections for each of said circuits, and controllable by-pass means for the respective parallel-resonant means.

13. The combination with an arc oscillator, of a tuned work circuit, a similarly tuned equivalent-energy circuit, circuit connections for connecting said circuits in parallel across said oscillator, parallel-resonant, reactive-impedance means tuned to approximately the same frequency as said circuits and connected in series relation to the circuit connections for each of said circuits, a by-pass path for each of said parallel-resonant means, and switching means for closing one of said paths and opening the other and vice versa, each of said parallel-resonant means having a relatively small resistance and relatively large inductive and capacitive reactances, each of said circuits likewise having, in effect, a relatively small resistance and relatively large inductive and capacitive reactances, said quantities being so chosen that there is little tendency for the oscillatory currents to flow in the circuit having the open-circuited by-pass path.

In testimony whereof, I have hereunto subscribed my name this 2nd day of August, 1921.

OMAR B. BUCHANAN.
